(57) **CLAIM**

The ornamental design for a scoop holder and base, as shown and described.

DESCRIPTION

FIG. 1 is an exploded perspective view of a scoop holder and base showing my new design;

FIG. 2 is an exploded rear elevation view thereof;

FIG. 3 is an exploded front elevation view thereof;

FIG. 4 is a top plan view thereof;

FIG. 5 is a bottom plan view thereof;

FIG. 6 is an exploded left-side elevation view thereof;

FIG. 7 is an right-side elevation view thereof;

FIG. 8 is a cross-section view taken along the line 8-8 in FIG. 1, the opposite view being the same in appearance; and, FIG. 9 is a perspective view of the scoop holder and base in an assembled condition.

The dashed lines are included for the purpose at illustration and form no part of the claimed design.
